UNITED STATES PATENT OFFICE.

JOHN F. O'CONNOR, OF CHICAGO, ILLINOIS, ASSIGNOR TO WILLIAM H. MINER, OF CHICAGO, ILLINOIS.

DRAFT-RIGGING FOR RAILWAY-CARS.

Specification of Letters Patent.

Patented Apr. 20, 1915.

1,136,042.

Application filed April 18, 1914. Serial No. 832,695.

To all whom it may concern:

Be it known that I, JOHN F. O'CONNOR, a citizen of the United States, residing at Chicago, in the county of Cook and State of Illinois, have invented a certain new and useful Improvement in Draft-Rigging for Railway-Cars, of which the following is a full, clear, concise, and exact description, reference being had to the accompanying drawings, forming a part of this specification.

My invention relates to improvements in draft rigging for railway cars.

The object of my invention is to provide a draft rigging of simple construction and efficient operation.

In the drawings forming a part of this specification Figure 1 is a side elevation partly in vertical horizontal section on line 20 1-1 of Fig. 2 of a draft rigging embodying my invention. Fig. 2 is a plan view partly in horizontal section. Fig. 3 is a cross section on line 3-3 of Fig. 2.

Referring to the drawings the numerals 4 indicate draft members or parts of the car frames to which the draft rigging is applied. A draw bar 5, is mounted between the draft members and is operatively connected to a draft yoke 6, the draft yoke comprising a pair of links 7, 7, a rear key 8 passing through transverse slots 9, 9, in the rear portion of the draft links 7 and extending at its ends through slots 10, 10 in adjacent portions of the draft members 4, the said slots 10, 10 being longitudinally extended to permit forward movement of the key 8 therein. The yoke 6, is connected to the draw bar portion (the rear only being shown in the drawings) by means of a coupler key 11, which passes through the transverse slots 12 in the forward portion of the links 7 and through a slot 13 transversely extending through the draw bar 5, the said slot 13 being forwardly extended to permit rearward movement of the draw bar without strain upon the key and the slots 12, 12 in the draft links 7 being rearwardly extended to permit the free movement of the key therein on rearward movement of the draw bar. A draft gear 14, is mounted between the draft links 7, the said draft gear comprising preferably a shell 15, and compression resisting elements 16 within the shell.

The numeral 17 indicates the front follower 55 lower and 18 the rear follower.

At its rear end the yoke is provided with a U-shaped member 19, one leg of which, 20, is mounted adjacent one of the links 7, the other leg, 21, being adjacent the other link 7. The said limbs are provided with transverse slots 60 registering with the slots 9 in the rear portion of the links and the rear key 8 passed through the same. The connecting member 22, between the limbs of the U-shaped members engages against the rear follower 18 in normal position of the draft rigging as illustrated in Figs. 1 and 2 of the drawings and in forward movement of the draft links in pulling movement of the draft rigging. The draft gear 14 is mounted 70 between upper and lower plates 23 and 24 respectively. These plates serve to form the stop members for the draft rigging, as hereinafter described. Each of these plates is preferably a channel shaped member. The 75 upper plate, in preferable construction, comprises a main web 25 and lateral upturned flanges at either edge 26. The lower plate 24 comprises a main web 27 and the lateral downturned flanges 28. The said plates 23 80 and 24 are each connected at either edge to the draft members, preferably by means of the rivets 29, 29 passing through their respective flanges through adjacent portions of the draft members. Each of said plates 85 is provided near its forward end with a vertical slot 30, the slot in the upper plate registering with the slot in the lower plate, the said slots being sufficiently longitudinally extended to permit the travel of the front 90 follower 17 therein in the operation of the draft rigging. The forward wall, forming the slot 30 in each plate, serves as a front stop shoulder 31 for the front follower, and the rear wall forming said slot in each plate 95 serves as a limiting stop shoulder 32 for the front follower. Near their rear ends the plates 23 and 24 are provided with vertical slots 33, 33 registering with each other and arranged to receive the rear follower 18 100 therein, the said slots 33, 33 being sufficiently forwardly extended to permit the travel of the rear follower therein in the operation of the draft rigging. The wall forming the rear edge of the slots 33 in the plates 23, and 105 24 forms the rear stop shoulder 35 for the rear follower 18 and the wall forming the forward edge of the said slots serves as a limiting stop shoulder 36 for the rear follower 18. In preferable construction the 110

slots 30 and the slots 33 in each of the plates 23 and 24 are provided along their edges with reinforcing members 37, 37, arranged transversely of the plates 23 and 24, the said members 37 preferably comprising angle irons secured to the plates by suitable means, preferably the rivets 38, 38.

- 5 In forward movement of the draw bar the key 11 is drawn forwardly, engaging 10 against the rear wall of the slot 13 in the draw bar and against the front walls of the slots 12 in the links 7, thus drawing the links 7 forwardly, the said links drawing the U-shaped member 19 forwardly against 15 the rear follower 18, which compresses the draft gear 14 against the front follower 17, the front follower being stopped by the stop shoulders 31, 31, provided in the plates 23 and 24.
- 20 On rearward movement of the draw bar the draw bar moves rearwardly upon the coupler key 11 and the forward extension of the slot 13 in the draw bar and the rearward extension of the slots 12 in the draft links permit the movement of the draw bar rearwardly without strain upon the key. The draw bar moves the front follower 17 rearwardly compressing the draft gear 14, the draft gear being stopped against rearward movement by the rear follower 18 which engages against the rear stop shoulders 35 in the plates 23 and 24. The stoppage of the front follower 17 against the front limiting stop shoulders 32 limits the rearward travel of the front follower and prevents the compression resisting elements of the draft gear 14 from being compressed solid. In mounting the draft gear in this position between the draft members the same 40 may be inserted between the plates 23 and 24 from the forward end of the car to which the same is applied through the forward opening formed by the draft members and the plates 23 and 24, thus obviating the lifting of the draft gear from underneath the car to its position between the draft members. The followers may then be placed in position at the ends of the draft gear through the front and rear slots of the 50 lower plate 24. The draft links may then be placed in their position between the sills from the forward end of the car, the member 19 placed in position and the rear key 8 passed through the draft links and the 55 member 19. The draw bar may then be

placed in position and the coupler key 11 inserted through the registering slots in the draft members, draft links and draw bar. If a change of draw bar becomes necessary, such change may be made by the removal of the keys 11 and 8 and withdrawing the same without disturbing the draft gear or the followers. If change of parts in the draft gear becomes necessary the same may be made by withdrawing the keys 11 and 8, 65 removing the draw bar, withdrawing the followers and drawing the draft gear forwardly where same may be examined and changes made without dismounting the same from between the sills. In case it is necessary to remove the shell the same may be done from the forward end of the car without the necessity of working in the space underneath the car. 70

Claims.

1. In a draft rigging for railway cars, in combination, draft members, a draw bar, a draft yoke connected to the draw bar, a draft gear, followers and upper and lower plates associated therewith, the said plates 80 being each provided with front and rear registering vertical slots, forming front and rear stop shoulders and front and rear limiting stop shoulders for the followers.

2. In a draft rigging for railway cars, the 85 combination with draft members, a draw bar, a draft yoke, followers and a draft gear, of upper and lower plates secured to the draft members and spaced apart to receive the draft gear between them, the draft gear 90 being receivable therein through the forward opening between said plates.

3. In a draft rigging for railway cars, in combination, draft members, a draw-bar, a draft yoke connected to the draw bar, upper 95 and lower substantially horizontally extending plates extending between and connected to said members, said plates being each provided with front and rear registering vertical slots intermediate their ends and 100 thereby forming stop shoulders, a draft gear mounted between said upper and lower horizontal plates and supported by the latter plate, and followers at the ends of said gear extending above and below the same and 105 into said slots.
